UNITED STATES PATENT OFFICE.

JOSEPH B. DESS, OF BALTIMORE, MARYLAND.

EXTENSION TABLE.

Application filed August 7, 1922. Serial No. 520,025.

To all whom it may concern:

Be it known that I, JOSEPH B. DESS, a citizen of the United States, residing at Baltimore city, State of Maryland, have invented certain new and useful Improvements in Extension Tables, of which the following is a specification.

This invention relates to tables having a round top which is adapted to be enlarged or increased in diameter by applying extension leaves to the edge thereof.

The invention has for its object to provide novel and improved means for supporting the extension leaves, and which latter, when not in use, may be supported beneath the permanent top of the table, completely out of the way and not exposed to view.

The invention also has for its object to pivotally support the table top so that it may be swung to assume a vertical position to afford more space in the room for cleaning, dancing, etc.

With the objects stated in view, the invention consists in a novel combination, and arrangement of parts to be hereinafter described and claimed, and in order that the same may be better understood, reference is had to the accompanying drawings, where-

30 in—
Figure 1 is an inverted plan view of the table top minus its supporting pedestal; Fig. 2 is a central vertical section of the table top and a fragment of the pedestal, the section being taken on the line 2—2 of Fig. 1; Fig. 3 is a sectional detail on the line 3—3 of Fig. 1; Fig. 4 is an elevation of the complete table showing the top swung to a vertical position; Figs. 5, 6 and 7 are 35 sectional details on the lines 5—5, 6—6, and 7—7 of Fig. 1; Fig. 8 is an elevation of a hinge connection between a pair of extension leaves, and Fig. 9 is a perspective view of one of the supporting arms of the extension leaves.

45 Referring specifically to the drawings, 10 denotes the permanent and stationary top of the table, the same being circular in form and supported by a center pedestal 11. To the under side of the top 10 is secured a batten or cross strip 12 which seats on a cap plate 13 secured to the top of the pedestal 11. A hinge connection is provided between the batten 12 and the cap plate 13 in order 50 that the top 10 may be swung to assume a vertical position as shown in Fig. 4, thereby

affording more space in the room for cleaning, dancing, etc. The hinges are shown at 55 15, and their leaves are countersunk in the cap plate 13 as shown in Fig. 2.

Near the edge of the table top 10, the latter is provided, on its under side, with an annular moulding strip 16 from which depends an annular rail 17 finished at its bottom edge with a moulding strip 18, these 60 members being all rigidly connected and forming a part of the table top.

Near the edge of the table top 10, the latter is provided, on its under side, with an annular moulding strip 16 from which depends an annular rail 17 finished at its bottom edge with a moulding strip 18, these 65 members being all rigidly connected and forming a part of the table top.

The extension leaves of the table are shown at 19, and they are all of uniform dimensions and segmental in shape so that 70 they may be positioned in a circular series around the edge of the top 10 flush therewith and thus increase the area thereof without destroying its circular form. These leaves are grouped in pairs, with the members 75 of each pair hingedly connected as shown at 20, the hinges being located at the outer and inner edges of the leaves so that the two leaves may be folded one on top of the other when they are to be stored away 80 beneath the table top as will be presently described.

At the site of the several joints between the leaves 19 are members for supporting the same in extended position encircling the 85 table top 10. Each of these members comprises a radially positioned arm 21 located beneath the table top and adapted to be slid outwardly to project from the edge thereof and form a support for the leaves. On the 90 under side of the arm 21 is a rib 22 which is increased in height near the outer end of the arm, and to said end of the arm, on the under side thereof, is fitted a moulding block 23 to which the rib extends. The rear end 95 of the rib 22 has projecting side pins 24, and near its outer end, the arm has longitudinal grooves 25 in its side edges. The purpose of the parts 24 and 25 will be presently described.

100 On the under side of the table top 10 are mounted supports for the arms 21. Each of these supports comprises a pair of laterally spaced and parallel rails 26 between which the arm 21 seats and is slidably supported, the inner edges of said strips being shaped so that the space therebetween corresponds to the cross-sectional contour of the arm 21 and its bottom rib 22, as clearly shown in Fig. 5. At the site of each arm 21, 105 the moulding 16 and the rail 17 is cut away 110 to form openings for letting the arms

through when they are slid outwardly to leaf-supporting position, and when said arms are slid back when the leaves are not in use, the moulding blocks 23 and the front 5 ends of the arms cover said openings so that the appearance of the table is not marred. The ends of the batten 12 are recessed, as shown at 27 to accommodate two diametrically opposite sets of the rails 26
10 The leaves 19 are supported in position for use by laying the same on the projecting ends of the arms 21 after the latter have been slid outwardly to extend beyond the edge of the table top 10. The outward 15 movement of the arms 21 is limited by the pins 24 abutting against the rear ends of the rails 26. In order to prevent upward displacement of the leaves, they are provided on the bottom with hook-shaped blocks 20 28 positioned to enter the side grooves 25 of the arms 21 as shown in Figs. 1 and 6. The leaves are further secured in position for use by latch bolts 29 mounted on the bottom thereof and adapted to enter the 25 grooves 25. Referring to Fig. 1, it will be noted that the blocks 28 are at the free ends of the members of the respective pairs of hingedly connected leaves, whereas the latch bolts 29 are at the hinged ends thereof. This arrangement enables the hooked 30 ends of the blocks 28 to be inserted into grooves 25 when the leaves are straightened out. Alternate ones of the arms 21 have their grooves entered by the hook-shaped 35 blocks 28, whereas the other arms have their grooves entered by the latch bolts 29.

When the leaves 19 are not in use, they may be stored away beneath the table top 10 as shown by dotted lines in Fig. 1, and for 40 this purpose there are mounted on the under side of said top and the under side of the batten 12, bracket members 30, and the bottom of the moulding 18 carries turn- 45 buttons 31. Each pair of leaves will be folded so that one leaf lies above the other, and the folded pair of leaves is then placed on a pair of bracket arms 30, and the turn- 50 button 31 is swung to come beneath the folded leaves. Figure 2 shows in dotted lines the leaves folded and stored away beneath the table top. The arms 21 will, of course, also be slid back beneath the table top, so that the latter now has the appearance of an ordinary round top table.
55 In order to divide the storage spaces for the leaves 19, there are mounted beneath the table top 10, wedge-shaped blocks 32, which are so positioned that they come between stored pairs of leaves and thus serve 60 as spacers for the same, as clearly shown in Figs. 1 and 5.

Referring to Fig. 3, it will be noted that

the moulding 16 projects slightly from the edge of the table top 10 so as to provide a support for the inner edge of the leaves 19, 65 the same seating on the projecting portion of the moulding.

I claim:

1. In an extension table, a permanent round top, a moulding on the under side thereof and projecting from its edge, a series of leaves for enlarging the area of the same, said leaves being arranged in hingedly connected pairs, radial arms supported beneath the table top and projecting from the edge thereof to support the leaves at their meeting edges, and with the inner edges of the leaves seating on the aforesaid projecting portion of the moulding, said arms being slideable inwardly to lie wholly beneath the table top, and having longitudinal side grooves, means carried by the pairs of leaves at the free ends thereof for holding the same against upward displacement, said means engaging the grooves of the arms coinciding with said free ends of the leaves, and latches carried by the pairs of leaves at the hinged ends thereof and engageable with the grooves of the arms coinciding with said hinged ends. 75 80 85 90

2. In an extension table having a permanent round top, a moulding on the under side thereof and projecting from its edge, a circumferential series of leaves for enlarging the area of the top, said leaves being arranged in hingedly connected pairs, radial arms supported beneath the table and mounted for longitudinal sliding movement to project beyond the periphery of the permanent top and support the leaves at 100 their meeting edges and with the inner edges of the leaves resting on the aforesaid projecting portion of the moulding, said arms being slideable inwardly to lie wholly beneath the table top and having longitudinal 105 side grooves provided with closed ends, certain of the arms supporting leaves at their free ends and other arms supporting said leaves at their hinged ends, lugs carried by the pairs of leaves at the free ends thereof for holding the same against upward movement, said lugs engaging the grooves of those arms supporting the free ends of the leaves, and latches carried by the series of leaves at the hinged ends thereof and engageable with the grooves of those arms supporting the hinged ends, said lugs and latches substantially filling the respective grooves whereby to limit the inward movement of the radial arms. 110 115 120

In testimony whereof I affix my signature.

JOSEPH B. DESS.
